[57] CLAIM

The ornamental design for an article holding device, as
shown and described.

DESCRIPTION

FIG. 1 is a top plan view of an article holding device
showing my new design;

FIG. 2 is a front elevational view thereof;

FIG. 3 is a bottom plan view thereof;

FIG. 4 is a fragmentary, side elevation view thereof; and,
FIG. 5 is a front and side elevation view of an article holding
device shown on a reduced scale in condition of use holding
a golf towel to a golf bag.The fragmentary criss-cross pattern shown in the drawing is
understood to represent woven cord and is repeated uniformly
throughout the areas shown.The broken line showing of a slidable clamping mechanism,
a golf bag and a golf towel are for illustrative purposes only
and form no part of the claimed design.
